UNITED STATES PATENT OFFICE.

WILLIAM H. ELKINS, OF CAMBRIDGE, MASSACHUSETTS, ASSIGNOR TO ALFRED D. TINGLEY, OF BOSTON, MASSACHUSETTS, AND HENRY E. IRVINE, OF NEW YORK, N. Y.

REGULATOR FOR DYNAMOS.

SPECIFICATION forming part of Letters Patent No. 427,163, dated May 6, 1890.

Application filed March 23, 1889. Serial No. 304,503. (No model.)

To all whom it may concern:

Be it known that I, WILLIAM HENRY ELKINS, of Cambridge, in the county of Middlesex and State of Massachusetts, have invented 5 a new and useful Regulator for Dynamos, of which the following is a specification, reference being had to the accompanying drawing, which is a diagram illustrating my invention, the pole-pieces and cores being shown 10 in dotted lines, and the circuit, which constitutes the main novelty, being shown in full lines.

My invention relates to regulating the potential of the work-circuit of a dynamo; and it 15 consists in a novel compound dynamo-circuit differing materially from all other dynamo-circuits known to me, as will now be fully explained.

In the drawing, A represents the armature, 20 and a the commutator, of an ordinary dynamo; B, the positive brush, and B' the negative brush, and B^2 an additional brush, the work-circuit being from the additional brush B^2 through the junction b and lamps $L L$ to main 25 brush B' . Conductors lead from junction b to the additional brush B^2 , and also to the main brush B through resistance R, this circuit from brush B through resistance R to junction b being the regulating-circuit.

In practical operation it is necessary to preserve a constant pressure or potential in the work-circuit $B' L L b$, the current varying as the number of lamps L varies. In the diagram I have shown five lamps or groups of lamps, so that the variable load may be divided into five portions. It will be found that the brush B^2 may be so adjusted in any given dynamo with a given speed that the desired pressure will be maintained over the work- 35 circuit $B' L L b$ when only one lamp out of the five—that is, one-fifth of the variable load—is used, the regulating-circuit $B R b$ being then open, or, what is practically the same thing, the resistance R being very large. Under 40 these conditions, if a second lamp or another fifth of the load be introduced into the work-circuit $B' L L b$, the pressure in the work-circuit will be decreased, for the speed of the dynamo will remain the same; but the resistance 45 is halved by doubling the load, and consequently the two lamps L, or two-fifths of the

total number of lamps, will not be at full candle-power. To remedy this the electro-motive force or pressure in the work-circuit $B' L L b$ must be brought up to the standard. A voltmeter in the work-circuit $B' L L b$ will indicate when the pressure in the work-circuit is thus decreased by the introduction of another fifth of the load, and the regulating-circuit $B R b$ will then be closed through resistance R, 55 which will be adjusted to bring the pressure at the point b nearer to the pressure in the brush B , and thereby bring the pressure in the work-circuit to the proper standard. When a third fifth of the load L is introduced, 60 the pressure in the work-circuit again decreases and is again brought to the standard by aid of the regulating-circuit by still further decreasing the resistance R, and so on until the whole load is in the work-circuit, when 70 the resistance R is eliminated, or practically so, the work-circuit then being from brush B to brush B' , practically as if the brush B^2 and resistance R were not present. My theory is that with maximum load the difference of potential between the main brush B and the junction b is at the minimum, the resistance R being then so small as to cause but slight fall of potential, there being but slight difference of potential between B and b under full load. 75 When the additional resistance is thrown into the work-circuit, other conditions being the same, less current flows through the entire circuit, including the armature-coils, and hence there is a greater difference of potential between the terminals of the machine; but the potential or pressure at the junction b will be kept constant, for the reason that b is connected directly to the brush B^2 and through resistance R to brush B, for the pressure 80 at junction b can be made substantially the same as the pressure in brush B by eliminating resistance R, or can be made substantially the same as the pressure in brush B^2 by making resistance R infinite, and can be 85 made more than in B^2 and less than in B by varying resistance R. For extreme range of regulation the brush B^2 may be drawn toward the brush B, or the brush B can be moved toward B^2 , as indicated by dotted line B^3 . 90

Theoretically, as I understand the matter, with a constant speed and a constant current

through the field-circuit $B' F F b$, the difference of potential between the terminals of the dynamo is at the minimum under full load when in multiple, and increases whenever the load is reduced, this being, as I understand it, because of the decreasing reaction of the armature upon the field-magnets as the current in the armature decreases, which practically makes the field stronger, even though the current in the field-circuit $B' F F b$ remain constant; and I therefore connect the junction b between the field and work circuits with both brushes $B B^2$, and I am thereby enabled to maintain the pressure constant at b , whatever be the change in the load.

What I claim as my invention is—

In a dynamo, the additional brush B^2 , the main brushes $B B'$, and the adjustable resistance R , additional brush B^2 being connected directly to the conductors forming the work-circuit and the conductors forming the field-circuit, and the brush B connected to the conductors through adjustable resistance R , all the brushes and conductors being arranged and operating, as described, to keep the pressure constant in the work-circuit by variations in the pressure supplied by the brushes B^2 and B , all substantially as set forth.

W. H. ELKINS.
